UNITED STATES PATENT OFFICE.

JOSEPH BAKOVICH, OF HERMINIE, PENNSYLVANIA.

RAILROAD-SWITCH-OPERATING DEVICE.

1,377,452.

Specification of Letters Patent. Patented May 10, 1921.

Application filed February 28, 1921. Serial No. 448,638.

To all whom it may concern:

Be it known that I, JOSEPH BAKOVICH, a citizen of Jugo-Slavia, residing at Herminie, in the county of Westmoreland and State of Pennsylvania, have invented certain new and useful Improvements in Railroad-Switch-Operating Devices, of which the following is a specification.

The primary object of the invention is the provision of ready means for operating a switch from a moving car whereby the motorman may control the travel of the car either upon the main track or a siding or branch track at will and without the aid of a switchman.

A further object of the invention is the provision of switch operating mechanism installed adjacent a railroad track, whereby a distantly positioned switch may be opened or closed at will during the travel of the car, thereby saving time and expense in connection with the operation of switches.

A still further object of the invention is to provide a switch operating mechanism operable from a moving train and possessing great strength or durability, as well as being simple in construction and easy and inexpensive to install.

With the above general objects in view and others that will appear as the nature of the invention is better understood, the same consists in the novel form, combination and arrangement of parts hereinafter more fully described, shown in the accompanying drawing and claimed.

In the drawing, wherein like reference characters indicate corresponding parts throughout the several views,

Figure 1 is a plan view of a railroad track partially broken away and shown with the present switch operating mechanism installed.

Fig. 2 is a sectional view drawn on a larger scale and taken upon line II-II of Fig. 1.

Fig. 3 is a still further enlarged view taken upon line III-III of Fig. 1, and

Fig. 4 is a vertical sectional view through a portion with the side of the car showing the adjustable actuator for the switch mechanism.

Referring in detail to the drawing the invention is herein illustrated in connection with a straight line of track having rails 10 and 11, the rail 11 being laterally curved to form one rail of a switch track or siding 12

in connection with the rail 13 parallel therewith. A movable switch point 14 is pivoted as at 15 to the end of the straight line track rail 11' for coöperating with the rail 11, 60 while a similar switch point 16 is pivoted as at 17 to the rail 13 for coöperating with the rail 10. The switch points 14 and 16 are connected by a transverse switch operating rod 18 which extends beyond one side of the rail 11 where it is provided with the usual weighted lever 19 for manually throwing the switch points should occasion so require. 65

The construction thus far described is old and well known in the art, and the present 70 invention provides an improved mechanism for the automatic shifting of the rod 18.

The actuating mechanism for the switch points 14 and 16, constituting the present invention, is mounted adjacent the straight 75 track 10-11 at a suitable distance from the switch points 14 and 16 and includes a horizontal base 20 preferably in the form of a metal plate which is embedded in cement as at 21 substantially flush with the surface of 80 the roadbed, the base 20 being provided with apertures at the ends thereof through which project upright posts 22 which have their lower ends embedded within the cement 21 and which are provided with aligned apertures through which a double rack bar 23 is slidably guided, the rack bar 23 being disposed parallel with the track rails 10 and 11 and being extended at one end to a point adjacent the hand lever 19 where it is attached slidably and pivotally as at 24 to one end of a bell-crank lever 25 which has its other end similarly connected as at 26 to the rod 18. In order to resist accidental movement of the rack bar 23, downwardly curved 95 leaf springs 27 are attached to the upright members 22 so as to have their lower free ends bearing upon the upper surface of the rack bar 23, the attaching means for the spring 27 preferably including adjusting 100 screws 28 whereby the friction of the springs upon the rack bar may be regulated.

The rack bar 23 has its opposite side edges toothed as at 29 and 30, and a pinion 31 meshes with the teeth 29 while a similar 105 pinion 32 meshes with the teeth 30, the pinions 31 and 32 being respectively fixed upon the lower ends of vertical shafts 33 and 34 which are journaled in suitable bearings 35 carried by upright posts 36 and 37. The 110 posts 36 and 37 extend through suitable openings provided therefor in the base plate

20 and have their lower ends embedded with-
in the cement 21, and the post 36 extends
upwardly to a greater height than the post
37 as clearly shown in Fig. 2. The shaft 33
5 has a lever 38 fixed thereto adjacent the top
of the post 36 so that the lever 38 normally
projects inwardly toward the rail 11 as
shown in Fig. 1. In a similar manner, the
shaft 34 has a lever 39 secured upon the up-
10 per end thereof directly beneath the lever
38 so as to normally project inwardly to-
ward the rail 11 as is also shown in Fig. 1.
If desired, the shaft 33 may be extended to
a point above the lever 38 so as to have a
15 signal lantern 40 mounted thereon whereby
the motorman of a car may readily ascertain
whether or not it is necessary for him to
throw the switch in order to proceed in the
desired direction.

20 In Fig. 4 is illustrated the carrying actuator for the levers 38 and 39 consisting of a lever 41 extending through an opening 42 in the side 43 of a car and pivoted therein as at 44, the lever 41 being provided with a
25 releasable spring catch 45 for coöperating with a curved rack 46 which is suitably fixed to the inside of the car concentric with the pivot 44. The lever 41 is provided with a transverse bar 47 upon its outer projecting
30 end, the bar 47 being suitably braced as at 48 and being disposed for engagement with a desired one of the levers 38 and 39 when the lever 41 is shifted from the neutral position of Fig. 4 to a position wherein the catch
35 45 engages either the upper notch 49 or the lower notch 50 of the rack 46.

With the parts positioned as shown in the drawing, we will assume that a car is ap-
40 proaching the switch moving toward the right of Fig. 1, it being the intention of the motorman to keep upon the straight line track. With this view, the catch 45 is re-
45 leased and the lever 41 is swung so as to en-
gage the catch 45 with the notch 49, where-
50 by the bar 47 is lowered so as to strike the lever 39. This causes rotation of shaft 34 so as to move the rack bar 23 toward the left, thereby swinging bell-crank lever 25 for causing movement of rod 18 whereby the switch point 14 is brought adjacent rail 11 and the switch point 16 is moved away from rail 10. Had the motorman desired to turn into the siding or branch track 12, he would have positioned the lever 41 in its neutral
55 position as shown in Fig. 4 so that the bar 47 would pass between the lever 38 and 39 without striking either one of the same. However, supposing that the switch points had been actuated as above outlined, and
60 that another approaching motorman wishes

to turn into the siding or branch track, he will set the lever 41 with the catch 45 en-
gaged in the notch 50 so that the bar 47 will strike the lever 38 for rotating pinion 31 and causing return of the rack bar 23, bell-
65 crank 25, rod 18 and switch points 14 and 16 to the position of the same shown in Fig. 1.

From the foregoing description, it is be-
lieved that the construction and operation
as well as the advantages of the present in-
vention will be readily understood and ap-
preciated by those skilled in the art.

Minor changes may be made without de-
parting from the spirit and scope of the in-
vention as claimed.

75

What is claimed as new is:—

1. Train-actuated operating mechanism
for switches comprising operatively con-
nected switch points, a rack operatively con-
nected to said points adapted for shifting
80 the points for permitting travel upon the
main track or a siding at will, operating
levers for the rack inwardly projecting to-
ward the track in different horizontal planes
and a bar carried by the train adapted for
85 adjustment for selectively engaging said
levers whereby the switch points are shifted
in either desired direction.

2. In combination with a railroad track
having a siding, switch points controlling
90 travel between the straight line track and
siding, an operating rack for the switch
points, pinions in constant mesh with the
opposite sides of the rack, shafts carried by
said pinions, and inwardly projecting levers
95 upon said shafts positioned at different ele-
vations adapted for selective contact during
the travel of a car upon the main track
whereby the switch points are actuated in
either desired direction.

100

3. In combination with a railroad track
having a siding, switch points controlling
travel between the straight line track and
siding, an operating rack for the switch
points, pinions in constant mesh with the
105 opposite sides of the rack, shafts carried by
said pinions, inwardly projecting levers
upon said shafts positioned at different ele-
vations, a bar pivoted for vertical shifting
upon the car traveling upon the track
110 adapted for selectively engaging said levers,
and adjustment-retaining means for said
bar.

4. A device of the class described comprising
switch points for a rack, actuating levers
therefor at different horizontal positions ad-
jacent the track adapted for moving the
switch points in either desired direction.

115

In testimony whereof I affix my signature.

JOSEPH BAKOVICH.
